SLIDE FASTENERS

William Mikulas, Staten Island, N. Y., assignor to Conmar Products Corporation, Newark, N. J., a corporation of New Jersey

Application August 20, 1953, Serial No. 375,406

9 Claims. (Cl. 24—205.11)

The invention relates to slide fasteners, and more particularly to means for improving the strength of the fastener at that end where the movement of the slider in fastener-opening direction is limited or stopped.

In one of the most common types of slide fastener, the lower ends of stringers are secured together immediately below the lowermost fastener elements or scoops by a so-called "permanent" bottom stop, as distinguished from a separable bottom stop assembly which permits the stringers to be disassembled. The strength of a fastener at the bottom stop is a highly important and determinative factor in assessing the quality of the product. The present invention relates to improvements in the construction of a slide fastener of the type having a permanent bottom stop.

One of the objects of the present invention is to construct the slide fastener so that the bottom stop will better resist the application of forces acting to displace it in a longitudinal direction.

Another object of the invention is to construct the fastener so that the bottom stop will better withstand the application of cross-pull forces upon the stringers which act to pull the beaded edges of the tapes out from within the stop.

The foregoing stated objects and other objects are accomplished by means of my novel slider. Also, the slider and bottom stop co-act in a wholly novel manner. In fact, the co-action of these two components of the fastener is such that the clamping strength of the bottom stop upon the tapes is actually increased a substantial amount beyond its initial or original holding power.

To the accomplishment of the foregoing objects, and such other objects which will hereinafter appear, my invention is directed to an improved slide fastener, particularly the slider thereof, and the co-action of the slider with the bottom stop, as sought to be defined in the appended claims, and as described in the following specification taken together with the accompanying drawing in which:

Fig. 1 is a partial plan view of a slide fastener embodying the principles of the present invention;

Fig. 2 is a perspective view, on an enlarged scale, of the bottom stop element of the slide fastener shown in Fig. 1;

Fig. 3 is a side elevation, on an enlarged scale, and partly in section, of the slider of the fastener shown in Fig. 1;

Fig. 4 is a plan view of the inside surface of the bottom wing of the slider shown in Fig. 3;

Fig. 5 is a partial plan view of a slide fastener of the prior art type, showing the relationship of the parts when the slider has been moved to its lowermost position to open the fastener, the top wing of the slider being omitted for the purpose of clarity in illustration;

Fig. 6 is a view similar to Fig. 5 showing the relationship of the parts of the fastener with my novel slider;

Fig. 7 is a partial side elevation, partly in section, showing the relationship of the slider of the present in-

2

vention and the bottom stop when the slider is in the position shown in Fig. 6, the stringers being omitted in this view for the purpose of clarity in illustration; and

Fig. 8 is a view similar to Fig. 7 illustrating another form of the invention.

Referring to the drawings, and particularly to Figs. 1 and 2, the slide fastener comprises the usual stringers 12 and 14, each provided with spaced interlockable fastener elements 16. The stringers 12 and 14 comprise tapes 18 provided with beaded or thickened edges 20 to which the fastener elements 16 are secured, as by clamping, casting or molding. The beaded edges may be formed in any suitable manner, as by sewing cords on opposite sides of the tape edges, or by weaving cords into the edge of the tape as an integral part thereof. The stringers 12 and 14 are connected together by a bottom stop B immediately below the lowermost scoop, the stop serving to limit the movement of the slider S in fastener-opening direction.

The bottom stop B is of a common and well-known variety, such as generally shown in the patents to Norton, 1,853,635, April 12, 1932; Seaver, 1,964,485, June 26, 1934; or Schaye, 2,575,187, November 13, 1951. More specifically, and as shown in Fig. 2, this stop comprises a pair of substantially parallel plates 22, 24 connected together at their lower ends by a narrow neck portion 26. The inner surfaces of the plates 22, 24 are provided with spaced indentations or grooves 28 which receive the beaded edges 20 of the tapes when the stop is clamped onto the tape edges. Thus, the beaded edges 20 are confined on top and bottom by the plates 22, 24 and laterally, or on the sides, by the central ribs 30 and the outside rails 32. The top edges 34 of the stop's plates are adjacent the lowermost scoops on the stringers, and the narrow neck portion 26 is located intermediate the stringers. For numerous reasons, dictated by the requirements of various operations of fastener manufacture and end usage, such as for gaging, enameling, sewing the fastener into the garment, etc., as well as for appearance, the bottom stop B has a width equal to the width of the scoops when engaged or meshed, and a thickness substantially equal to the thickness of the scoops. Thus, when the slider is moved all the way to the bottom of the fastener to open same, the bottom stop B is received within the slider's internal channel.

The slider S is of the usual variety, except for a novel structural change which hereinafter will be described. The slider comprises spaced top and bottom wings 36, 38 joined at their upper ends by a neck or post 40. The top wing is provided with inturned rails or flanges 42 and the bottom wing with inturned rails or flanges 44, which together with the neck or post 40 form the usual Y-shaped internal channel C. A pull tab 46 is secured to a lug 48 provided on the top wing 36 to permit the slider to be moved up and down along the stringers. The slider S may be formed in any suitable fashion, as by stamping, molding or die-casting, and may be of the non-locking, pin-lock, wing-lock, friction-lock or automatic locking type. The non-locking type of slider is illustrated for simplification of illustration only, and, as thus far described, the slider may be of any conventional type or structure.

As shown in Fig. 5, when an ordinary slider, designated S', is moved downwardly or in fastener-opening direction, the movement of the slider is halted when its neck portion 40' engages the top edges 34 of the bottom stop B. If, as sometimes occurs, the slider is moved downwardly with unduly great force, the impact of the neck portion upon the top edges of the bottom stop will cause the clamping strength of the stop upon the beaded edges of the tapes to be exceeded, and results in the bottom stop

being displaced downwardly in the direction of the arrows x .

Another weakness of the ordinary fastener is evident when it is subjected to cross-pull causing the stringers to be pulled in the direction of the arrows y , as shown in Fig. 5. With the slider S' in this fully opened fastener position, the fastener elements 16 are no longer supported in the slider. The full cross-pull forces exerted upon the stringers are taken by the beaded edges of the tapes in a direction substantially perpendicular to the rails 32 of the bottom stop, or at their corners, designated 50 . These are the weakest points of the bottom stop, because they are at the mouth end, and furthermore from the connecting neck portion 26 at the other end. The beaded edges 20 will pull out of the stop's grooves 28 .

To materially improve the ability of the bottom stop B to withstand the forces tending to displace it along or across the stringer tapes, as hereinbefore described, the slider is simply provided with a projection P , as shown in Figs. 3, 4, 6 and 7, or P' , as shown in Fig. 8. The projection is formed on the inside surface of a wing and projects into the internal channel of the slider a distance sufficient to engage the bottom stop and halt the movement of the slider before the slider can move down far enough for the neck portion to engage the bottom stop. The projection is located intermediate the neck portion and the bottom of the slider, and is spaced from both. As shown in Fig. 6, there are several scoops on each stringer which remain within the slider when the projection engages the bottom stop. Instead of the cross-pull forces upon the stringers being taken entirely by the comparatively weak points 50 of the bottom stop, several scoops 16 now in the slider bear against the inturned flanges 42 and 44 of the slider. The greatest part of the cross-pull forces is distributed across the comparatively strong inturned flanges of the slider against which the plurality of scoops bear, and only a very small component of force is taken by the weak corners 50 of the stop.

Preferably, the projection and the bottom stop have co-acting means whereby the pressure of the projection against the stop will cause the stop to clamp the beaded tape edges with increased holding power, thereby increasing the bottom stop's ability to withstand forces acting to longitudinally displace it, or to separate it from the tapes in a lateral direction. As shown in Figs. 3 and 7, the projection P is provided with a bevel or inclined surface 52 on at least its side facing the bottom stop. Although the inclined surface is only needed on that side facing the bottom stop, it is convenient in manufacturing the slider to simply throw up a substantially frusto-conically shaped projection on the inside of a wing, as shown. When, as shown in Fig. 7, the slider S is moved downwardly, and the projection P is pressed against the upper edge of plate 24 of the bottom stop, the plate moves up on the projection causing the plates to be cammed or pressed towards each other and against a wall of the channel.

In order to realize maximum camming action, or increased clamping pressure upon the bottom stop plates, the projection is preferably located in the upper half of the slider, or between the arm portions of the internal Y-shaped channel. Also, it is preferred to position the projection on the median longitudinal axis of the slider. The slider wings' maximum resistance to spreading apart is at the neck portion, and diminishes toward the mouth end of the slider. Thus, to realize the maximum camming effect, while permitting as many scoops as possible to be positioned within the slider channel when the projection engages the stop, it is preferred to position the projection between the neck portion and the upper end of the stem portion of the slider's internal channel.

While it is preferred to use a conventional bottom stop B , which has not been altered, to cooperate with the described slider, the advantages of the invention may be realized by altering the bottom stop slightly and utilizing

a slider formed with a straight-sided projection. As shown in Fig. 8, the bottom stop, designated B' , is provided with an inclined surface 54 on one of the plates $24'$ for coaction with the projection P' , so that when the projection engages and presses against the inclined surface 54 , the plates, $22'$, $24'$, are caused to be pressed towards each other and against a wall of the channel.

While the projection P has been shown as formed in only one wing, the lower wing of the slider, it will be obvious that it may also be formed in the upper wing instead, or in both wings. Also, though the frusto-conically shaped projection is preferred, the projection may be given any suitable form to accomplish the described purposes and functions.

It is believed that the novel construction of the described slide fastener, including the novel slider and its co-action with the bottom stop, as well as the advantages thereof, will be apparent from the foregoing detailed description. It also will be apparent that while I have shown and described a preferred form of my invention, changes may be made therein without departing from the spirit and scope of the invention, as sought to be defined in the following claims.

I claim:

25. 1. A slide fastener comprising a pair of stringers each having spaced interlockable fastener elements secured to the beaded edge of a tape, a slider comprising a pair of spaced wings connected at one end by a neck portion and having inturned flanges to thereby provide a substantially Y-shaped internal channel for engaging and disengaging the fastener elements, the spacing between said wings being slightly greater than the corresponding dimension of the fastener elements to allow free movement of the slider, and a permanent bottom stop connecting the stringers together, said bottom stop being located immediately below the lowermost fastener elements on the stringers, and having dimensions which permit it to be received within said internal channel, said slider being provided with a projection formed on the inside surface of a wing and projecting into the internal channel of the slider a distance sufficient for engaging said bottom stop and halting the downward movement of the slider, said projection being located intermediate said neck portion and the upper end of the stem portion of the Y-shaped channel so as not to interfere with the free movement of the slider, the relationship of the parts being such that fastener elements on the stringers are positioned within the internal channel of the slider when the projection is in engagement with the bottom stop, whereby the fastener elements within the slider will bear against said inturned flanges formed on the inside surface of a wing.

2. A slide fastener comprising a pair of stringers each having spaced interlockable fastener elements secured to the beaded edge of a tape, a slider comprising a pair of spaced wings connected at one end by a neck portion and having inturned flanges to thereby provide a substantially Y-shaped internal channel for engaging and disengaging the fastener elements, the spacing between said wings being slightly greater than the corresponding dimension of the fastener elements to allow free movement of the slider, and a permanent bottom stop connecting the stringers together, said bottom stop being located immediately below the lowermost fastener elements on the stringers, and having dimensions which permit it to be received within said internal channel, the bottom stop being of the type which comprises a pair of opposed plates clamped onto the beaded edges of the tapes, said slider being provided with a projection formed on the inside surface of a wing and projecting into the internal channel of the slider a distance sufficient for engaging said bottom stop and halting the downward movement of the slider, said projection being located intermediate said neck portion and the upper end of the stem portion of the Y-shaped channel so as not to

interfere with the free movement of the slider, the relationship of the parts being such that fastener elements on the stringers are positioned within the internal channel of the slider when the projection is in engagement with the bottom stop, whereby the fastener elements within the slider will bear against said inturned flanges formed on the inside surface of a wing, said projection and a plate of said bottom stop having coating means whereby the pressure of said projection against said plate will cause the plates to be pressed towards each other and against a wall of the channel.

3. A slide fastener comprising a pair of stringers each having spaced interlockable fastener elements secured to the beaded edge of a tape, a slider comprising a pair of spaced wings connected at one end by a neck portion and having inturned flanges to thereby provide a substantially Y-shaped internal channel for engaging and disengaging the fastener elements, the spacing between said wings being slightly greater than the corresponding dimension of the fastener elements to allow free movement of the slider, and a permanent bottom stop connecting the stringers together, said bottom stop being located immediately below the lowermost fastener elements on the stringers, and having dimensions which permit it to be received within said internal channel, the bottom stop being of the type which comprises a pair of opposed plates clamped onto the beaded edges of the tapes, said slider being provided with a projection formed on the inside surface of a wing and projecting into the internal channel of the slider a distance sufficient for engaging said bottom stop and halting the movement of the slider, said projection being located intermediate the neck portion and the upper end of the stem portion of the Y-shaped channel so as not to interfere with the free movement of the slider, said projection having an inclined surface on that side thereof which engages said bottom stop, whereby the pressure of said projection against a bottom stop plate will cause the plates to be pressed toward each other.

4. The slide fastener of claim 2 in which the said coating means includes the forming of said projection in substantially frustro-conical shape.

5. The slide fastener of claim 1, in which the projection is stamped on the inside surface of the lower wing of the slider and is located on the median longitudinal axis of the slider.

6. A slider for use with slide fasteners of the type comprising a pair of stringers each having spaced interlockable fastener elements secured to the beaded edge of a tape and a permanent bottom stop connecting said stringers and limiting the movement of the slider in fastener-opening direction, said slider comprising a pair of spaced wings connected at one end by a neck portion and having inturned flanges to provide a substantially Y-shaped internal channel for engaging and disengaging the fastener elements, the spacing between said wings being slightly greater than the corresponding dimension of the fastener elements to allow free movement of the slider, and a projection formed on the inside surface of a wing and projecting into the internal channel of the slider a distance sufficient for engaging said bottom stop and halting the movement of the slider, said projection being located intermediate said neck portion and the upper end of the stem portion of the Y-shaped channel so as not to interfere with the free movement of the slider.
7. The slider of claim 6 in which the projection has an inclined surface on that side thereof which engages the bottom stop.
8. The slider of claim 6 in which the projection is substantially frustro-conical in shape, is stamped on the inside surface of the slider lower wing and is located on the median longitudinal axis of the slider.
9. The slide fastener of claim 3 in which the projection is stamped in frustro-conical form on the inside surface of the lower wing of the slider and is located on the median longitudinal axis of the slider.
